Letters Patent No. 2163 Dated Aug 15, 1865.

Design for a Sign

The schedule referred to in these letters patent and making part of the same

To all whom it may concern

Be it known that of Ezechel Berg of
the City, county and State of New York, have

originated and designed a new device for Show
Signs for Sugar & Tobacco Stores, designated a
Sugar Tree, of which the following is a full, clear,
and exact description, reference being had to the
accompanying drawings, making a part of this
Specification.

The Sugar Tree is composed of a trunk, or
large sugar or imitation of a sugar A Fig 1 set
perpendicularly on a stand or platform B Fig 1.
Attached to this large sugar or trunk are affixed
smaller sugars or imitations of sugars C, C, Fig 1
angularly radiating upwards like the branches
of a tree.

Fig 2 is a sectional view of the sugar tree.
What I claim as my invention and desire to secure
by letters patent is the design for show signs for
Sugar & Tobacco Stores as herein shown and
described.
